UNITED STATES PATENT OFFICE.

KENNETH P. MONROE, OF PENNS GROVE, NEW JERSEY, ASSIGNOR TO E. I. DU PONT DE NEMOURS & COMPANY, OF WILMINGTON, DELAWARE, A CORPORATION OF DELAWARE.

PROCESS OF MAKING TETRA-ALKYL LEAD.

No Drawing.

Application filed March 25, 1924. Serial No. 701,641.

This invention relates to the production of a tetra-alkyl lead, and comprises, as a new process, the interaction of a lead-sodium alloy with an alkyl chloride and a neutral hydroxylic compound (preferably functioning catalytically) which is soluble in said chloride, and preferably in the presence of another catalyst and of an inert diluent.

As I have pointed out in my U. S. Patent 1,645,389, dated October 23, 1927, the synthesis of lead-alkyls from lead-sodium alloy and an alkyl bromide is promoted by the addition of water either per se or in a diluted state. I have now discovered that the synthesis of lead-alkyls from lead sodium alloy and an alkyl chloride resembles the bromide synthesis in this respect, despite the lesser chemical reactivity of the chloride, and have made the additional discovery that the water 20 may be replaced, either wholly or in part, by another neutral hydroxylic compound, such as ethyl or propyl alcohol.

These hydroxylic compounds (water, alcohol, etc.) have a great influence on the course of the reaction, being in fact essential from a practical manufacturing standpoint. If highly purified alkyl chloride (or bromide) is permitted to react with pure lead sodium alloy the yield of lead alkyl is negligible under the same conditions which result in a substantial yield when alkyl chloride (or bromide) containing an appreciable amount (for example 0.4% based on the weight of alkyl halide) of water or an alcohol is used. On the other hand the presence of an excessive initial amount (for example 4.0%) of water or an alcohol causes excessive side reaction (for example, the evolution of hydrogen) and causes a diminution 40 in yield from that obtained when an optimum amount is present. The addition of alcohol or water may be made entirely in the beginning, or in portions from time to time as the reaction proceeds. This latter procedure may serve as a mode of control for obtaining a smooth reaction, particularly when the reaction is carried out on a large scale and is, therefore, more liable to sudden and disastrous temperature surges. It 50 has also been found desirable to assist in the control of the reaction on the larger scale by dilution of the liquid reaction mass with an inert miscible liquid; such liquid may be, for example, benzene or other inert hydro-

carbon which is miscible with the alkyl 55 chloride used.

The invention may be illustrated by the following examples:

(1) 100 grams very pure lead-sodium alloy containing 14.6% sodium (the composition of the alloy being expressible as a mixture of 44 parts of PbNa with 56 parts of PbNa₂) was placed in a steel tube with 60 cc. highly purified ethyl chloride. The tube was closed and placed in an oil bath where 65 it was rotated while the temperature was gradually raised to 80° C. and maintained at 80° C. for eight hours. The tube was then removed, cooled, opened and the contents thoroughly extracted with dry, alcohol-free ether. On filtration and evaporation of the ether only a vanishingly small yield (1/2 cc.) of lead tetra-ethyl was obtained.

(2) 100 grams very pure lead-sodium alloy containing 14.6% sodium was placed in a steel tube with 60 cc. highly purified ethyl chloride to which 1 1/4 cc. absolute ethyl alcohol had been added. The tube was then closed and placed in an oil bath where it 80 was rotated while the temperature was raised gradually to 80° C. and maintained at 80° C. for eight hours. The tube was then removed, cooled, opened, and the contents thoroughly extracted with dry, alcohol-free 85 ether. On filtration and evaporation of the ether 15 1/2 cc. lead tetra-ethyl were obtained.

(3) 100 grams lead-sodium alloy containing 14.6% sodium were placed in a steel tube with 130 cc. ethyl chloride containing 90 0.4% alcohol and water. 5 cc. additional ethyl alcohol were then added. The tube was closed, placed in an oil bath, and rotated while the temperature was gradually raised to 65° C. and maintained at 65° C. 95 for 48 hours. The tube was then opened and the excess ethyl chloride and lead tetra-ethyl separated from the residual lead by steam distillation. 2 cc. lead tetra-ethyl were obtained.

(4) 100 grams lead-sodium alloy containing 14.6% sodium were placed in a steel tube with 130 cc. ethyl chloride containing 0.4% alcohol and water. The tube was closed, placed in an oil bath, and rotated while the 105 temperature was gradually raised to 65° C. and maintained at 65° C. for 48 hours. The tube was then opened and the excess ethyl

chloride and lead tetra-ethyl separated from the residual lead by steam distillation. 19 cc. lead tetra-ethyl were obtained.

The reaction using an ethyl chloride, as 5 will have appeared in the above examples, is preferably carried out at a temperature above 60° C. as compared with the temperature of 25-30° C. which gave best results with ethyl bromide as described in my said 10 copending application. It is to be understood, however, that my invention is not limited to working at any particular temperature or temperatures.

Instead of water or alcohol per se to aid 15 the reaction, I may use, as above indicated, water or alcohol diluted by dissolving therein a salt or hydroxide such as potassium carbonate, potassium hydroxide, sodium chloride, or a salt of a metal whose hydroxide is 20 insoluble or only slightly soluble, such as magnesium and calcium chlorides.

The hydroxylic compound used seems to act as a true catalyst, being continually regenerated during the progress of the reduction by a secondary reaction between the sodium hydroxide (or alcoholate) and the hydrochloric acid formed. This accounts for the effectiveness of the small proportion of hydroxylic compound used.

30 Where it is found desirable to use an additional catalyst, such catalyst is preferably of the type used for the Grignard synthesis, such for example as tertiary amines (dimethylaniline, pyridine, etc), esters (ethyl 35 acetate), ethers, etc.

I claim:

1. The process of producing a tetra-alkyl lead from a lead alloy and an alkyl chloride, which comprises treating one atomic proportion of lead, alloyed with two atomic proportions of a monovalent element capable of liberating hydrogen from water, with an alkyl chloride in the presence of less than 5.1 molecular percentage, based upon said 45 chloride, of a neutral hydroxylic compound soluble in the alkyl chloride.

2. The process of producing a tetra-alkyl lead from a lead alloy and an alkyl chloride, which comprises treating one atomic proportion of lead, alloyed with two atomic proportions of a monovalent element capable of liberating hydrogen from water, with an alkyl chloride in the presence of from about 0.5 to 1.3 molecular percentage, based upon 55 said chloride, of a neutral hydroxylic compound soluble in the alkyl chloride.

3. The process of producing a tetra-alkyl lead from a lead-sodium alloy having a sodium content of about 14.6 percent and an alkyl chloride, which comprises treating the lead-sodium alloy with the alkyl chloride in the presence of from about 0.5 to 1.3 molecular percentage of a neutral hydroxylic compound, soluble in said chloride, to enable the combination between the lead and

the alkyl chloride to proceed, by the addition of the hydroxylic compound at such a rate that excessive evolution of free hydrogen is avoided.

4. A process as defined in claim 1 in which 70 the alkyl chloride is ethyl chloride.

5. A process as defined in claim 2 in which the alkyl chloride is ethyl chloride.

6. A process as defined in claim 3 in which the alkyl chloride is ethyl chloride.

7. A process as defined in claim 3 in which the alkyl of the alkyl chloride contains from 1 to 4 carbon atoms.

8. The process of producing tetra-ethyl lead which comprises inducing a reaction 80 between an alloy of the formula $PbNa_2$, ethyl chloride, and water in an amount less than 4 percent based upon the weight of the ethyl chloride, and recovering the tetra-ethyl lead formed.

9. The process of producing tetra-ethyl lead which comprises inducing a reaction between an alloy of the formula $PbNa_2$, ethyl chloride, and water and alcohol in an amount less than 4 percent based upon the 90 weight of the ethyl chloride, and recovering the tetra-ethyl lead formed.

10. The process of producing tetra-ethyl lead which comprises maintaining, at a temperature above 60° C., a mixture containing 95 an alloy of the formula $PbNa_2$, ethyl chloride, and from about 0.2 to 2.0 percent of water based upon the weight of ethyl chloride present, until the reaction is about completed.

11. A process as defined in claim 10 in which a mixture of water and ethyl alcohol is used in place of water.

12. The process of producing tetra-ethyl lead which comprises gradually adding a 105 neutral hydroxylic compound soluble in ethyl chloride to a mixture containing the lead-sodium alloy $PbNa_2$ and ethyl chloride, the amount of hydroxylic compound present at any one time in the reaction mixture 110 being just sufficient to enable the combination between the lead and the ethyl chloride to proceed, by the addition of the hydroxylic compound at such a rate that excessive evolution of free hydrogen is avoided.

13. The process of producing tetra-ethyl lead which comprises gradually adding water to a mixture containing ethyl chloride and the alloy $PbNa_2$, the amount of water present at any one time in the reaction mixture 115 being not substantially in excess of that required to enable the combination between the lead and the ethyl chloride to proceed actively, by the addition of the hydroxylic compound at such a rate that excessive evolution of free hydrogen is avoided.

14. The process of producing tetra-ethyl lead which comprises gradually adding water to a mixture containing ethyl chloride and the alloy $PbNa_2$, the amount of water 125

present at any one time in the reaction mixture being not substantially in excess of that required to enable the combination between the lead and the ethyl chloride to proceed actively, by the addition of the hydroxyl compound at such a rate that excessive evolution of free hydrogen is avoided, and maintaining the reaction mixture at a temperature above 60° C., throughout the 10 major part of the reaction period.

15. The process of producing tetra-ethyl lead which comprises gradually adding water and ethyl alcohol to a mixture containing ethyl chloride and the alloy PbNa₂, the 15 amount of water and alcohol added amounting to between 0.2 and 1 percent, based upon the weight of ethyl chloride present.

16. A process as set forth in claim 13 in which ethyl alcohol replaces at least a substantial part of the water which is added to 20

the mixture of ethyl chloride and lead-sodium alloy.

17. Process of making an alkyl compound of a metal of the second sub-group of the fourth periodic group, comprising alloying 25 the metal with a highly electro-positive metal, and treating the alloy under reaction conditions with an alkylating agent in the presence of a hydrocarbon liquid.

18. The process of making a lead ethyl 30 which comprises reacting a lead-sodium-alloy with an ethylating agent in the presence of a hydrocarbon liquid.

19. The process of claim 18 in which the hydrocarbon liquid is a lower hydrocarbon 35 of the benzene series.

In testimony whereof I affix my signature.

KENNETH P. MONROE.
